COMBINATION OF BOOK MATCHES AND
TOOTHPICKSGiuseppe Maresca, Jackson Heights, N. Y., and
Giovanni Pannone, Waterbury, Conn.

Application June 15, 1940, Serial No. 340,658

2 Claims. (Cl. 206—29)

This invention relates to new and useful improvements in a combination of book matches and tooth picks.

The invention has for an object the construction of an article as mentioned which is characterized by a conventional book of matches provided with a sheet of tooth picks mounted within the cover thereof and adjacent the matches in a manner so that one tooth pick may be removed at a time, as desired.

Still further the invention proposes the provision of means for separating the matches from the tooth picks in a sanitary fashion.

Still further the invention contemplates the use of Cellophane, or other similar sheet material, arranged to comprise the sanitary separating means referred to in the previous paragraph.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a combination of book matches and tooth picks constructed in accordance with this invention.

Fig. 2 is a vertical sectional view taken on the line 2—2 of Fig. 1.

Fig. 3 is an elevational view of the sheet of tooth picks used in the article, and illustrated per se.

Fig. 4 is an end elevational view of Fig. 1.

Fig. 5 is a fragmentary vertical sectional view taken on the line 5—5 of Fig. 4.

Fig. 6 is a fragmentary horizontal sectional view taken on the line 6—6 of Fig. 5.

Fig. 7 is a sectional view similar to Fig. 5 but illustrating the parts in different positions.

The combination of book matches and tooth picks, in accordance with this invention, includes sheets of paper matches 10 disposed within a cover 11 having an openable front portion 11a. A sheet of tooth picks 12 is disposed within the cover 11 adjacent the sheets of matches 10. A sheet of sanitary material 13 separates the tooth picks and the matches. A staple 14 engages through the sheets of matches and tooth picks, the sanitary sheet 13, and the cover 11 for holding the parts together as a unit.

The sheets of matches 10 are of conventional construction formed from cardboard in the usual way. The cover 11 is of sheet cardboard, and

in addition to the openable front portion 11a, has a back portion 11b which at its bottom end continues into a front flange portion 11c extending upwards over the bottom edges of the sheets of matches 10. This flange portion 11c is provided with the usual match striking material 15. The sheet of tooth picks 12 comprises a thin sheet of wood having a transverse base portion 12a from which the tooth picks proper 12b project. The arrangement permits the tooth picks proper 12b to be broken off from the base 12a when it is desired to remove them for use.

A second sanitary sheet 13' is used to separate the cover 11 from the tooth picks 12. This sanitary sheet 13' has a top portion 13a which is bent over the top ends of the tooth picks proper 12b and which continues into an upwardly extending end portion 13aa. A narrow strip of metal 16 is attached along the end portion 13aa, and has each end projecting from a side of the cover 11, and continuing into a hook portion 16a which slidably engages the edge of the cover 11. The upper ends of the tooth picks 12b are disposed behind the upwardly bent end portion 13aa. Thus the upper ends of the tooth picks which are intended to be used to pick particles from the teeth are encased in the top portion of the sheet 13' and are maintained in a sanitary condition.

When the cover 11 is opened by moving upwards the front openable end 11a, and the strip 16 is moved upwards on the cover 11 to a position as indicated in Fig. 7 in which the bent portion 13a is located above the top ends of the tooth pick portions 12b, then a tooth pick may now be removed from the package. The strip 16 may be slipped downwards to place the parts back into the position shown in Fig. 4 in which the upper ends of the remaining tooth picks are again protected.

While we have illustrated and described the preferred embodiment of our invention, it is to be understood that we do not limit ourselves to the precise construction herein disclosed and the right is reserved to all changes and modifications coming within the scope of the invention as defined in the appended claims.

Having thus described our invention, what we claim as new, and desire to secure by United States Letters Patent is:

1. A combination of book matches and tooth picks, comprising a sheet of paper matches, a cover encasing said matches and having an openable end portion, a sheet of tooth picks within said cover and adjacent said matches, a sheet of sanitary material separating said tooth picks

and matches, a staple holding said matches, tooth picks and sanitary sheet on said cover, and a set-in sanitary sheet separating said cover and tooth picks and being secured within said cover by said staple, one of said sanitary sheets having a top edge portion engaging over the top ends of said tooth picks, and means for holding said edge portion in a lowered position engaged over the tooth picks or in a raised position moved free of the tooth picks, comprising a strip attached on said edge portion and having hook elements at its ends slidably engaged on the edges of said cover.

2. A book of matches having a cover encasing a sheet of paper matches, a sheet of toothpicks within said cover adjacent said matches, a sheet

of sanitary material between said matches and toothpicks, and a second sheet of sanitary material disposed between the other face of said sheet of toothpicks and the adjacent wall of said cover,
5 5 one of said sanitary sheets having its top edge portion bent downwards engaging over the top ends of the toothpicks completing the encasement of said sheet of toothpicks between the adjacent faces of said sanitary sheets, and means
10 for holding said top edge portion in a lowered position over said toothpicks or in a raised position in which the top ends of said toothpicks are free to be individually separated from said sheet of toothpicks.
